UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A GOBLET OR SIMILAR ARTICLE.

46,642.

Specification for Design.

Patented Nov. 10, 1914.

Application filed May 20, 1914. Serial No. 839,908. Term of patent 7 years.

To all whom it may concern:

Be it known that I, ANDREW J. SANFORD, a citizen of the United States, residing at Newark, Ohio, have invented a new, original, and ornamental Design for a Goblet or Similar Article, of which the following is a specification, reference being had to the accompanying drawing, forming part thereof.

Figure 1 is a side elevation of a goblet illustrating my design; Fig. 2 is a horizontal section taken on the line 2—2 of Fig. 1, looking upwardly. Fig. 3 is a similar section taken at about the same plane, to wit, at 3—3 of Fig. 1, looking downwardly.

The chief characteristic of this invention is a goblet composed of a narrow, deep body,

surmounted upon a comparatively short stem, the major portion of the body of the receptacle being composed of contiguous vertical panels which extend well up toward the rim of the vessel and terminate at the stem. These panels are wider at the top portion and gradually narrowed toward the stem.

I claim:

The ornamental design for a goblet or similar article, substantially as shown and described.

ANDREW J. SANFORD.

Witnesses:

MAUD BETTS,
H. C. MUELLER.
